UNITED STATES PATENT OFFICE.

JAY TAMASSY, OF NEW YORK, N. Y.

BAG CLOSURE.

Application filed April 29, 1926. Serial No. 105,405.

This invention relates to bags and fastening means therefor, and more particularly refers to a simple and inexpensive way of sealing bags such as are used for holding a small quantity of tea leaves or other substances adapted to make an infusion.

The primary object of this invention is to provide a novel and improved means for closing the mouth of a bag, said means being inexpensive, simple in design and extremely efficient.

Another object is to provide a novel type of seal for closing the mouth of a bag, so formed that tampering with the seal will be easily detected.

A further object is to provide a bag seal of a novel and improved design, which is adapted to be set and formed in position by automatic machinery or by some specially designed tool; so that the cost of the seal itself as well as the cost of applying it to the neck of a bag is negligible although the result obtained is positive and effective.

Other objects and advantages of the present invention will more fully appear as the description proceeds and will be set forth and claimed in the appended claims.

The ordinary method of closing a bag after filling it is, of course, to gather its folds at the mouth forming them into a neck and tying a string around it. This method is both slow and expensive, and is hardly satisfactory where quantity production methods are needed.

Certain types of bags, such as those small bags such as are used for holding a small quantity of tea leaves, adapted to be immersed in hot water in order to produce a certain quantity of tea infusion, are produced in large quantities and must necessarily be of an inexpensive character; at the same time this type of product requires a positive as well as inexpensive method of sealing the bags in order to protect the contents thereof.

A number of seals of various designs have been proposed and used for this purpose, but while the sealing action provided by these devices is fairly satisfactory, I have found that generally these seals may be easily removed and replaced in position; I have also found that some of these seals in time become loose, their grip on the folds of the bag becoming less positive and permitting the escape of part of the contents of

the bag if the bag should by chance be turned upside down.

Due to the nature of the products which are sold in these containers, it is highly desirable that the contents of the bags be held safely and surely within the bag by a seal which is not liable to become loose of its own accord.

It is also desirable that this seal be of such a nature as to prevent any attempt to tamper with the contents of the bag for the purpose of substituting an inferior product, or even for the purpose of refilling an empty bag for resale purposes.

My present invention has for its object to produce a type of seal which may be used for all sorts of bags and which is particularly well adapted for tea or coffee cartridge bags, possessing all the desirable features mentioned both in regard to its cost and in regard to its effective action.

In the accompanying drawings, I illustrate a typical embodiment of my invention, and referring to said drawings—

Fig. 1 is a view in perspective of a tea cartridge embodying my invention;

Fig. 2 is a fragmentary view in elevation of the neck portion of the bag used in Fig. 1, showing a different flexible suspension means, in an enlarged scale; and

Fig. 3 is a plan sectional view through the neck of the bag in Fig. 2.

Referring to Fig. 1, 10 designates a bag of a suitable fabric, preferably open mesh, adapted to contain a predetermined quantity of tea leaves or coffee. The mouth of the bag is closed by gathering together its edges into folds and then it is maintained in this position by applying to its neck portion a metallic seal 11 which clamps and holds together the said folds.

A bag of this nature is usually also provided with flexible suspension means which are used to hold the bag into a cup or kettle of hot water. Ordinarily, a string is applied to the bag for this purpose merely by slipping one of its free ends between the bag and the ring embracing the neck of the bag, the other end of said string being provided with a tag which may be used as a handle; however, the string attached to the bag in this manner is liable to and often does easily slip off, so that some inconvenience in the handling of the bag may be caused thereby.

In the production of bags of this character, I prefer to secure the string to the bag in such a manner that slippage of the string cannot occur; for instance, in the device shown in Fig. 1, 12 designates a tag attached to the free end of a string or wire 13, the free end of which is inserted between the seal 11 and the bag in the usual manner; however, the free end of the string has been tied into a knot 14, which will effectively prevent slippage of the string, assuring the permanency of the connection.

However, this method of attaching the string to a bag complicates manufacturing operations to a certain extent, and I have found preferable and equally as effective to sew or to attach a string directly to the upper part of the bag as shown in Fig. 2, where 13' designates the string and 14' the point of attachment of the string to the bag.

Referring now to the main object of my invention, a positive and permanent closure of the bag is effected by first gathering the edge of the bag's mouth into folds, pressing them together to form a neck closing the bag and then by applying a seal to said neck portion embracing and retaining said folds together.

This object is attained by using a single length of metallic wire which is inserted through the neck of the bag until the neck is about midway of the length of the wire; the two projecting ends of the wire are then bent around the neck in the same direction, so that one of the ends embraces that part of the folds which is at one side of the part of the wire inserted through the neck, and the other end embraces that part of the folds which is located at the other side. Thus when the device is inserted in position it roughly resembles an S in shape with its curved parts preferably long enough to reach or even to overlap the ends of the transversal intermediate portion.

Thus in Fig. 3, it will be observed that 15 designates the intermediate portion of the original straight wire inserted through the neck of bag 10. Said wire is bent at opposite points 16, 17, as close to the surface of the neck as possible, and its end portions are wound about the neck to form substantially semi-circular loops 18, 19, encircling the folds of said neck.

The wire so used should be stiff enough to resist any tendency of the folds to expand so as to hold the bag securely closed; at the same time it should preferably be hard to unbend without undergoing permanent deformation or breakage, so as to make it impossible to remove the seal and then to replace it after tampering with the contents of the bag. The material should therefore possess a certain degree of brittleness, making the material unfit to stand any excessive amount of bending and unbending. When

the string is attached to the bag by clamping it between the seal and the bag, for instance, in the manner shown in Fig. 1, it is advisable to have the wire of which the seal is constituted long enough to completely encircle the neck of the bag, so that the free ends of the wire reach the points 16, 17, where the bends of the wire originate, abutting against the surface of said bends or even extending a little bit beyond the points 75 of bending. This prevents the possibility of the string slipping out of the seal sideways, so that it insures a safe hold of the bag by means of the string at all times.

In the case of bags of ordinary size this type of seal may be placed in position by hand or by means of an ordinary pair of pliers, as well as by machinery or by automatic production methods; but in the case of small bags such as used to hold a small quantity of tea leaves or coffee, it is very difficult to place the seal in position without the aid of some specially designed machine; therefore, this makes it all the more difficult for any one to open the seal and replace it. Labor costs are so important an item in the production of articles of this kind, that the moment the sealing operation is made too long or too difficult to be performed by hand, tampering with or adulteration of the 90 contents of a bag as well as the production of imitation products subject to misrepresentation, automatically become unprofitable and these unfair practices are therefore discouraged before they are attempted.

My improved device is also advantageous purely on the ground of cost when compared to other devices heretofore employed for the same purpose; because due to its design the device lends itself to be applied automatically or semi-automatically from a continuous length of wire which may be inserted, cut off, bent and formed in one operation and in a very short time, the length of the wire employed for each device being adjusted or adjustable to suit.

The wire is preferably of a round section which is generally more rigid than an equivalent flat section, so that for the same result a saving of metal may be effected by using a round wire rather than a flat strip; however, a flat strip may be used if desired or if special considerations should make it preferable.

In the case of large bags, the contents of 120 which may be valuable, tampering with the contents of the bag may be prevented in a still more effective and certain manner by spot welding the very end of each of the bent portions of the wire to the surface of 125 the other at the point where it meets it; in the present case the meeting point coinciding with the starting point of the bends 16, 17. In this case it would become necessary to actually break the wire before it could be 130

removed at all, so that this system could be used for instance, for sealing bags of registered mail and other bags, the contents of which is valuable. It would not be advisable however and it is not necessary to resort to this extra precaution in the case of tea leaves or coffee bags used for infusion purpose.

The bent portions of the wire may be somewhat shorter than a full semi-circle and still provide an effective closure, but on the other hand they may also be longer than represented so that each may be made to fully encircle the neck of the bag one or more times.

The wire or strip metal used may be made of any suitable metal or alloy, and the device itself may be produced in any suitable manner, the device per se, and a bag in combination with the device forming the essence of the present invention independently of the methods which may be used in forming and applying the device to the bag.

The invention may be varied in its minor details without departing from the inventive idea and accordingly the drawings are intended for illustrative purposes only, and not in a limiting sense. Therefore, I reserve myself the right to carry my invention into practice in any way or manner which may enter fairly into the scope of the appended claims.

I claim:

1. As a new article of manufacture, a bag seal consisting of a continuous length of relatively stiff wire, comprising a central portion inserted through the neck of the bag, and opposite extensions therefrom, one extension being bent about one part of the neck of the bag and the other extension being

bent about the other part of the neck of the bag whereby to clamp the same by the stiffness of said wire.

2. As a new article of manufacture, a bag seal consisting of a continuous length of relatively stiff wire, comprising a central portion inserted through the neck of the bag, and opposite extensions therefrom, one extension being bent about one part of the neck of the bag and the other extension bent about the other part of the bag, and flexible suspension means attached to the bag.

3. An infusion material container, comprising an open mouthed bag made of flexible fabric, having its mouth closed by gathering its folds together to form a neck, a seal therefor consisting of a continuous piece of wire inserted through said neck and having opposite end extensions, one extension passing around one part of said neck, and the other extension extending around the other part of said neck, said extensions being reversely bent around said neck.

4. An infusion material container, comprising an open mouthed bag made of flexible fabric, having its mouth closed by gathering its folds together to form a neck, a seal therefor consisting of a continuous piece of wire inserted through said neck and having opposite end extensions bent reversely about said neck whereby one extension is bent around one part of the neck and the other extension is bent around the other part of the neck to securely clamp the same, and flexible suspension means clamped between one of said extensions and the neck of the bag.

JAY TAMASSY.
